DISHWASHING MACHINE

William Norris Harris, Atlanta, Ga.

Application October 6, 1941, Serial No. 413,885

1 Claim. (Cl. 134—115)

- 1** The invention relates to dish washing machines. The primary object of this invention is the provision of an improved dish washing machine designed to be readily adapted for use with a sink of conventional design requiring a minimum of change in such a sink.
- An additional object is the provision of a dish washing device which will provide for improved cleansing of articles positioned therein.
- A still further object is the provision of a dish washing apparatus which may be readily utilized with a sink of conventional design and removed therefrom with a minimum of difficulty in order to permit the sink to be utilized in the normal manner.
- A still further object is the provision of such a device which will be reliable and efficient in operation and of durable and economical construction.
- Other objects will in part be obvious and in part be pointed out hereinafter.
- The invention accordingly consists in the combinations of elements, features of construction and arrangements of parts all as will be more fully pointed out hereinafter and disclosed in the accompanying drawings, wherein:
- Figure 1 is a perspective view of a sink incorporating this improved dish washing device having the cover associated therewith in place.
- Figure 2 is a top plan view of the sink having the cover and certain other elements of the device removed therefrom.
- Figure 3 is a top plan view of the driving mechanism adapted to be utilized in conjunction with certain movable elements of this invention.
- Figure 4 is an enlarged plan view of the sink disclosing the dish containing basket, which comprises a feature of the invention, in position therein.
- Figure 5 is a side sectional view of the device of this invention showing certain of the operating mechanism.
- Figure 6 is an end elevational view of the basket shown in Figures 4 and 5.
- Figure 7 is a view similar to Figure 6 taken from the opposite end of the basket.
- Figure 8 is a side elevational view of a constructional detail.
- Figure 9 is a side sectional view, certain parts thereof being broken away, of the assembly of certain of the operating mechanism of this device.
- Figure 10 is a view similar to Figure 9 but disclosing a substitution of certain parts for certain other parts disclosed in Figure 9.
- 2** Similar reference characters refer to similar parts throughout the several figures of the drawings.
- Having reference now to Figure 1 there is generally indicated at 20 a sink which may be of substantially conventional design associated with which are hot and cold water spigots 21 and 22 respectively both adapted to flow into a common exit pipe 23.
- An additional pipe 16 leads from the hot water inlet pipe to an automatic measuring valve 17 of any desired conventional type, from which a discharge pipe 18 leads to an outlet 18a positioned in the side of sink 20 (see Fig. 2). An operating handle 19 controls the operation of valve 17.
- Valve 17 is so constructed that movement of handle 19 permits the passage of a predetermined quantity of water into the sink. Thus when it is desired to utilize the sink as a dishwasher it may be filled to that capacity productive of maximum efficiency in a substantially automatic manner. Sink 20 is also provided with a drain pipe 24 opening into the bottom of the sink as at 25 (see Figure 2).
- In suitable apertures 26 (see Figure 9) to be more fully described hereinafter are positioned propellers 27 adapted to be rotated in a manner and for a purpose to be described hereinafter which extend upwardly above the bottom of the sink a substantial distance. Adapted to be positioned within the sink is a mesh wire basket generally indicated at 30 adapted for the reception of dishes, glasses, silverware and analogous articles to be washed. Certain of the wires 31 of basket 30 are so formed as to form pockets or apertures completely surrounding and shielding propellers 27 from contact with the chinaware to be washed. Certain other wires 32 define slots or pockets into which small plates may be inserted. Others, 33 define pockets of greater extent for the reception of larger articles of chinaware. Additional wires 34 (see Figures 4 and 6), are so arranged as to provide pockets especially adapted to contain cups, portions of these pockets, comprising wires 35, being so designed as to provide accommodation for the handles of said cups.
- All of the above-mentioned wires are associated with the base of the basket or container. Additionally certain other wires 36 are positioned in relatively close relationship above a fine wire mesh section 37 designed to accommodate silverware in up-ended relationship to permit ready drainage thereof.
- Extending above the base surface of the bas-

ket are a series of further wires 38 so formed as to provide pockets for glasses or tumblers, it being noted that the pockets so formed are inclined to permit the reception of the glassware in angularly inclined inverted position facilitating ready drainage thereof.

Pivoted as at 40 to one end of basket 30 is an arrangement of wires generally indicated at 41 forming a plurality of additional pockets 42 also adapted for the reception of glasses or tumblers. Extending wire hooks 43 adapted to engage the sides of basket 30 (see Figures 4 and 6) retain device 41 in its proper position when pivoted into position over the basket. It will be noted that arrangement 41 overlies wires 35 formed for the reception of cups and accordingly, the diameter of the cups being relatively small as compared to that of plates, portion 41 may be folded over such cups when the device is to be utilized, thus effecting a material saving in space. Suitable handles 45 are provided to facilitate the ready insertion into and removal of the basket from sink 20.

From the foregoing it will now be seen that basket 30 may be removed from the sink, filled with chinaware and silverware, etc., or all the dishes requiring washing after a meal, and deposited in sink 20 preparatory to washing such dishes. After the washing has been effected, in a manner to be described hereinafter, basket 30 may, by means of handles 45, be readily removed from the sink to facilitate drainage and drying of the cleansed dishes.

Referring now back to Figure 1 there is generally indicated at 50 a cover member adapted to completely enclose the sink when the washer is in operation. Cover member 50 is adapted to engage a peripheral groove 51 positioned entirely about the edge of sink 20 and in which may be positioned a gasket 52 of soft rubber or analogous material to prevent leakage when the device is in operation.

A suitable aperture 53, provided with a movable closure member 54, is positioned in the top of cover 50 to permit filling of the sink while the cover is in place. Closure member 54 may, if desired, be of glass in order to permit observation of the operation of the device or the water level therein when the cover is in position.

It may here be pointed out that pipe 23 is rotatable and it is desirable that opening 53 be located in a position in the arc of rotation of the discharge nozzle of pipe 23. Cover 50 is also provided with handles 55 to facilitate removal and replacement thereof.

It should also be noted that there is positioned within drain 24 a pop-up valve (not shown) of conventional design controlled by a lever 56 attached to a rod 57 controlled by a push button 58 located outside cover 50 whereby the sink may be drained, if desired, without removal of the cover.

Having reference now to Figure 9 it will be seen that the apertures 26 in the bottom of sink 20 are provided with bushings 60 and packing gaskets 61 within which are adapted to rotate drive shafts 62 to which are fixedly attached drive pulleys 63. Suitably threaded retaining members 69 engaging corresponding threads or projecting portions of sink 20 serve to retain bushing 60 and gaskets 61 in related assembly. The opposite ends of shafts 62 may be journaled in bushings 64 positioned in any suitable extending projections 65 depending below the level of sink 20.

The upper ends of drive shafts 62 are provided with recesses 66 in the walls of which are cut one or more grooves 67. Propellers 27 are provided with shafts 68 with which are associated one or more splines 69 adapted to engage grooves 67 whereby rotation of shafts 62 occasions rotation of propellers 27.

It will thus be seen that propellers 27 may be readily removed from recesses 66 in drive shafts 62 when desired by the simple expedient of pulling them upwardly out of the recesses. In such case and when it is desired to use sink 20 for other purposes than washing dishes, suitable closure members 70 (see Figure 10) provided with spring fingers 71 are provided and adapted to be inserted into recesses 66 whereby to completely close the bottom of the sink for any purpose as desired.

Having reference now to the means for rotating propellers 27 there is provided an electric motor 80 of any desired type adapted to be secured to the wall adjacent the sink, or in any other desired location. Motor 80 is provided with a driving pulley 81 with which is associated a drive belt 82 which in turn engages all of pulleys 63. Thus it will be seen that upon the actuation of motor 80 in a manner to be described hereinafter, the propellers 27 are all caused to revolve simultaneously and at uniform speed.

As shown in Figure 1 a push button type switch 85 is provided for the energization of motor 80. Switch 85, however, is connected in series with a second push button type switch 86 in such manner that energization of the motor is precluded unless both switches are closed. A wedge-shaped projection 87 (see Figure 8) is provided on cover 50 adapted to engage push button 86 to close that portion of the circuit associated therewith when the cover is in position. Accordingly motor 80 cannot be energized unless the two switches are simultaneously closed, which fact precludes the energization of the motor and hence rotation of the propellers when the cover member 50 is not in place, to avoid the throwing of water about the room as might otherwise be the case.

The operation of the device should now be readily understood. When it is desired to use the device as a dish washer, assuming that cover members 70 are in position, they are first removed and propellers 27 inserted into their associated recesses 66. Soiled dishes are then stacked in basket 30 at any suitable location, basket 30 then being positioned in the sink, as best shown in Figure 5. The sink may now be filled with water through valve 17 and inlet 18a, and soap or other suitable cleansing agent and cover 50 placed thereover. If desired, cover 50 may, of course, be positioned first and the sink filled through aperture 53. After the cover member is in place, which placement, closes switch 86, push button 85 is closed starting the motor 80 which in turn rotates propellers 27 at a desired speed, thoroughly diffusing the soapy water over and into all the articles to be washed positioned in the basket 30.

It may here be pointed out that basket 30 is so designed and propellers 27 so positioned as to insure the most effective dissemination of the cleansing fluid over all the surfaces of the plates, glassware, silver, etc. positioned in the basket.

After the cleansing operation is continued a sufficient length of time depression of button 58 will open the valve in drain 24 and permit drainage of the sink. After the sink is drained, the valve may be reclosed and the sink refilled with rinsing water through aperture 53 in cover 50

whereupon the propellers may be restarted and fresh water thoroughly disseminated over all the articles to be washed, to rinse the same. Upon the conclusion of one or more rinsing operations, cover 50 may be removed and basket 30 may be placed in a suitable location to permit the dishes to drain after which they may be removed therefrom for drying.

It will be readily understood that while there are shown herein four propellers, a greater or less number may be utilized if desired and that while the driving means herein shown is a belt and pulley arrangement, any other suitable drive mechanism, such as flexible shafting, may be employed.

Now from the foregoing it will be seen that there is herein provided a device accomplishing all the objects of this invention and many others including advantages of great practical utility.

As many embodiments may be made of this inventive concept and as many modifications may

be made in the embodiment herein described and shown it is to be understood that all matter hereinbefore set forth or disclosed in the accompanying drawings is to be interpreted merely as illustrative and not in a limiting sense.

I claim as my invention:

A device of the class described for a sink having an opening and an exterior projecting portion about said opening, and a bracket on the exterior 10 of said sink, the device comprising a shaft adapted to be journaled in said opening and said bracket, packing around the shaft at the outer end of said portion, a cap about said shaft for engaging said portion and enclosing said packing, 15 said shaft in the top thereof having an axially extending recess to selectively receive attaching means of a propeller or attaching means of a closure, and operating means for said shaft between said cap and bracket.

W. NORRIS HARRIS.
